(57) **CLAIM**

I claim the ornamental design for a light reflector, as shown and described.

DESCRIPTION

FIG. 1 is a front perspective view of the light reflector;
FIG. 2 is a rear perspective view of the light reflector;
FIG. 3 is a side view of the light reflector;
FIG. 4 is a front view of the light reflector; and,
FIG. 5 is a rear view of the light reflector.
